G. W. Lage,

Gate Latch.

NO. 97.934.

Patented Dec. 14, 1869.

FIG. I.

FIG. 2.

P. W. Large
INVENTOR.
By his attys,
Knight Bros.

ATTEST:

United States Patent Office.

GEORGE W. LARGE, OF YELLOW SPRINGS, OHIO.

Letters Patent No. 97,934, dated December 14, 1869.

IMPROVED LATCH.

The Schedule referred to in these Letters Patent and making part of the same.

I, GEORGE W. LARGE, of Yellow Springs, Greene county, Ohio, have invented a new and useful Improvement in Gate-Latches; and do hereby describe the same.

Nature and Objects of the Invention.

My improved latch, in its complete form, consists, essentially, of a rigid latch on the gate, a gravitating-catch on the latch-post dropping in front of the latch to retain it, and a "rolling lifter," to carry up the latch to its position behind the catch, without friction; said lifter serving further, preferably, to elevate the catch for the passage of the latch beneath it, and to support the gate against sagging, and also, if desired, to assist in opening the gate.

The provision in said lifter, in the connection named, constitutes my invention.

General Description.

In the accompanying drawings—

Figure 1 is a perspective view of a gate, fitted with my improvement, and open.

Figure 2 is a side view of the latter, partly in section, and in the closed position.

A, B, and C are, respectively, the hinge-post, the latch-post, and the gate, which parts may have the usual, or any preferred form.

The latch proper, D, is firmly attached to the gate C.

Attached to the face of the latch-post B is a bracket, E, to which is pivoted, by means of a pintle, e, an L-shaped lever or rolling lifter, F.

The horizontal portion *f* of the lifter F has sufficient weight to hold the said lifter, when the gate is open in the position shown in fig. 1, (and in dotted lines in fig. 2.)

The upwardly-extending portion *f'* of the lifter F has a curved part, *f''*, and an upward projection, *f'''*, to receive the impact of the latch-bar when the gate is being closed.

The gate-post B has a recess, G, to receive the part *f'''* of the lifter, when the gate is closed.

Above the recess G is attached a metallic plate, H, to which is secured a gravitating-catch, I, by means of screws or rivets *h*, which occupy a vertical slot, *i*, in the catch.

The operation of the latch is as follows:

When the gate is closing, the rigid latch D impinges against the upward projection *f'''* of the lifter F, and

carries back the same until it enters the recess G in the latch-post, the said projection rising, in passing the gravitating-catch I. When the latch has passed beneath the catch, the latter slides downward, and engages the latch, as seen in fig. 2.

When it is desired to open the gate, the catch I is raised, and the gate may then be readily opened.

The horizontal part of the lifter may (if preferred) be made of sufficient weight to throw open the gate, when the catch is raised.

It is impossible for cattle to unfasten or open the gate, as the catch projects but a slight distance from the gate-post, and is preferably located so high thereon that no part of the animal will come in contact therewith.

The gate cannot be thrown up by stock, as the fixed-latch, when the gate is closed, fits immediately beneath the lower end of the plate H, to which the gravitating-catch is secured.

The latch and lifter being arranged on the face of the post, as shown, which the latter is adapted for, by its peculiar construction, the use of a latch, of such length as to insure proper engagement with the catch in all conditions of the gate, is permitted, and the latch further enabled to abut against the post.

In its employment to elevate the catch, it greatly facilitates this, affording an upward pressure.

While preferring the L-shape for my rolling lifter, it is proper to state that any other form may be employed, whose weight will depress the lifter, when the gate is open, in the manner explained.

The screw or rivet-holes in the latch D may be extended endwise, to form slots, and by that means render the latch adjustable.

Claim.

I claim, as my invention—

The employment, in combination with a rigid latch, D, on the gate, and a gravitating-catch, I, arranged on the face of the latch-post, and dropping in front of the latch, to retain it, of a pivoted or rolling lifter, F, as and for the purposes set forth.

In testimony of which invention, I hereunto set my hand.

G. W. LARGE.
